FLORIST'S WIRE TWISTING MACHINE

Theron E. Reynolds and Everett Fyffe, Lodi, Calif., assignors, by direct and mesne assignments, to Farmers and Merchants Bank of Lodi, Calif.

Application September 22, 1945, Serial No. 617,986

20 Claims. (Cl. 140—93)

1

This invention relates to, and it is an object to provide, an automatic, power driven machine operative to twist florist's wires onto the stems of flowers intended for use on floral pieces, or the like. It is the present practice to manually twist the wires onto the flower stems, which procedure requires considerable time and is tedious to the florist. With the present machine, the wires are power twisted onto the flower stems rapidly and effectively; the florist being required to do no more than hold the flower stem in engagement with a projecting half-loop of the wire which the machine will next twist.

An additional object of this invention is to provide a florist's wire twisting machine which includes a normally stationary but rotary plate provided with means to releasably clamp a preformed dual leg wire in predetermined position thereon with one leg substantially longitudinally aligned with the axis of rotation of the plate, and the other leg diverging therefrom, whereby a flower stem placed along said one leg will have the other leg wrapped or twisted thereabout upon rotation of the plate; said plate being driven, to twist each wire, through a certain number of revolutions by means of an electric motor-driven mechanism including an automatic control circuit associated therewith.

A further object of the invention is to provide a florist's wire twisting machine, as above, including a novel magazine unit arranged to automatically feed the individual wires to the rotary wire twisting plate; said magazine unit being movable relative to the twisting plate and actuated by the electric motor-driven mechanism in predetermined timed relation to rotation of said plate.

A further object of the invention is to provide a florist's wire twisting machine, as in the preceding paragraph, in which the wire twisting plate rotates about a horizontal axis, and the magazine reciprocates vertically; the electric motor-driven mechanism and control circuit being operative to cycle the parts to first rotate the plate through its certain number of wire twisting revolutions, the plate stopping in a horizontal position, and to then reciprocate the magazine unit to and from the plate to feed another wire thereto.

A further object of the invention is to produce a simple and inexpensive device, and yet one which will be exceedingly effective for the purpose for which it is designed.

These objects are accomplished by means of such structure and relative arrangement of parts as will fully appear by a perusal of the following specification and claims.

2

In the drawings similar characters of reference indicate corresponding parts in the several views:

Figure 1 is a side elevation of the machine showing the wire twisting plate in its normal horizontal position, and the wire feeding magazine in its normal raised position.

Figure 2 is a similar view, but shows the magazine as lowered to feed a wire to the twisting plate.

Figure 3 is a front elevation of the machine, with the front plate removed.

Figure 4 is a cross section on line 4—4 of Fig. 3 showing the details of the wire feeding magazine, with the parts thereof in their normal retracted positions.

15 Figure 5 is a similar view but shows the parts of the magazine upon feeding of a wire to the twisting plate.

Figure 6 is a fragmentary front elevation of the parts of the wire feeding magazine corresponding in position to Fig. 4.

Figure 7 is a fragmentary front elevation, as in Fig. 6, but shows the parts of the feeding magazine corresponding in position to Fig. 5.

25 Figure 8 is a plan view of the wire twisting plate as in use, after the first revolution thereof.

Figure 9 is a similar view of the twisting plate, as in use, but after two revolutions thereof.

30 Figure 10 is a diagrammatic front elevation of the gear drive and overrunning clutch arrangement for the separate shafts which drive the wire twisting plate and the movable wire feeding mechanism.

Figure 11 is a fragmentary elevation, partly in section, of the motor reversing switch control 35 device; said device being shown in the position which it occupies at the start of the wire twisting cycle of the machine.

Figure 12 is a fragmentary elevation, partly in section, of the motor reversing switch control 40 device; said device being shown in the position which it occupies at the start of the wire feeding cycle of the machine.

Figure 13 is a diagram of the electric control circuit.

45 Referring now more particularly to the characters of reference on the drawings, the machine comprises a horizontal base 1 having an upstanding front panel 2 mounted thereon. To the rear of, and spaced a substantial distance from, the front panel 2, the base 1 is formed on top thereof with a motor support 3, on which a reversible electric motor 4 is mounted, with the drive shaft 5 of said motor projecting horizontally forward.

The shaft 5 is coupled to a reduction gear assembly 6, which in turn drives a countershaft 7

journalized in a frame structure 8 which upstands from the motor support 3 ahead of the motor 4. Below the countershaft 7 there is another countershaft 9 journalized in the frame structure 8 in parallel relationship. At their forward ends and in front of the frame structure 8 the shafts 7 and 9 are fitted, respectively, with gears 10 and 11; said gears having two to one ratio whereby the gear 11 makes two full revolutions for each revolution of the gear 10.

An overrunning clutch, indicated generally at 12, is coupled between the shaft 9 and the gear 11, whereby the latter is driven by said shaft 9 only when the same rotates in the direction shown by the arrow in Fig. 10.

Ahead of the gear 11 the shaft 9 is fitted with an attachment head 13, to which a flat plate 14 is secured adjacent one end; said plate radiating from the axis of rotation of the shaft 9 and being affixed to said attachment head 13 with said axis intersecting the plate adjacent but short of one end of the latter. It will thus be seen that with rotation of the shaft 9 the plate will be swung thereabout, with the plate facing in the direction of rotation.

At the forward corner adjacent the axis of rotation of said plate the latter is notched or cut away, as at 15, and in front of said notch the front plate 2 of the machine includes a vertical slot 16 enlarged adjacent the bottom, and which enlargement is in substantially the plane of the plate 14 when the same is in its normal horizontal position.

The plate 14 is maintained in such normal horizontal position by a spring catch 17 which permits of rotation of said plate therewith in the direction shown in the arrow in Fig. 3, but limits retractive movement of the plate in the opposite position below horizontal. The direction of rotation of the plate 14, as indicated in Fig. 3, corresponds of course to the direction in which the shaft 9 is driven by the gear 11 through the medium of the clutch 12, which latter overruns in the opposite direction.

The plate 14 is provided, on the normally top surface thereof, with a pair of wire receiving clamps 18, said clamps each including, in a suitable mount, a pair of vertically aligned, engaged, ball-type jaws 19. The clamps 18 are adapted to releasably but frictionally engage the separate and divergent legs 20 and 21 of a florist's wire, indicated generally at 22, and which wire is of substantially the same type as shown in copending application, Serial No. 562,199, filed November 6, 1944.

The clamps 18 are positioned on the plate 14 so that the leg 20 of each florist's wire 22 is held in connection with said plate adjacent and substantially parallel to the axis of rotation thereof; the other clamp being disposed in laterally offset relation and adjacent the forward edge of the plate, whereby to clampingly engage the leg 21. The clamp 18 which engages the leg 20 thus faces laterally at right angles to said axis of rotation of the plate, while the other clamp 18 is disposed some distance from such axis in rearwardly and laterally inwardly facing relation.

The florist's wire 22 is formed, intermediate its ends, with a forwardly projecting, initially un-twisted half loop 23, and when the wire is secured to the rotary plate 14, said half loop 23 projects forwardly through the vertical slot 16 in the front panel 2. To twist the wire about a flower stem 24, said stem is projected through the vertical slot 16 on top of the half loop 23 and along the adjacent

portion of the leg 20. The operator then manually holds the half loop 23 and the stem 24 in positive engagement between his fingers, and in the manner hereinafter described in detail the electric motor is then energized to cause one full revolution of the countershaft 7, which results, through the two to one gears 10 and 11, in two full revolutions of the countershaft 9 and plate 14. When this occurs the leg 21 is wrapped twice about said engaged stem 24 and leg 20, as shown in Fig. 9. Upon completion of the two full turns of the plate 14 it is held in its normal horizontal and starting position by the spring catch 17. In order to permit the plate 14 to rotate about the stem 24 and leg 20 inwardly of the front panel 2, said plate is notched and cut away at the adjacent corner, as at 15, as previously described.

The manner in which operation of the motor 4 is initiated and automatically terminated will be hereinafter described:

After a florist's wire has been twisted onto the stem 24 of a flower the operator merely withdraws the then twisted wire outwardly through the slot 16 with the stem 24. Another florist's wire is then disposed in secured relation on the plate 14 for a subsequent operation; the florist's wire being automatically fed in timed relation to said plate 14 by a wire feeding magazine structure comprising the following:

The magazine structure, indicated generally at 25, comprises a housing 26 mounted for vertical reciprocation above the twisting plate 14 by means of a transversely spaced vertical pair of guide sleeves 27 on the back of housing 26 slidably disposed on vertical posts 28 upstanding from the base 1. Compression springs 5 surround the posts 28 between the base 1 and the sleeves 27; said springs tending to move the magazine structure 25 upwardly to its normally elevated position. Reciprocation of the magazine structure 25 between its normally raised position and a lowered position in engagement with the normally horizontal twisting plate 14 is accomplished through the medium of a crank 29 on the forward end of countershaft 7; the outer end of the crank being connected to the magazine structure in operative relation by means of a pivotally attached link 30. The crank 29 is normally maintained in a vertical position by means of a spring detent 31 mounted on top of the frame, whereby the magazine structure 25 is correspondingly maintained in its normally raised position.

An overrunning clutch 32 is coupled between the shaft 7 and the crank 29, whereby motion is imparted to said crank from the shaft only when the latter turns in the direction shown by the arrow in Fig. 10. It will thus be noted that when the reversible motor 4 is driven in one direction the shaft 7 will run free relative to the crank 29, and at which time the shaft 9 is driven, through the clutch 12, to rotate the twisting plate 14. However, when the motor is driven in the other direction the twisting plate remains stationary in its normally horizontal position and the shaft 7, with each full revolution thereof, rotates the crank to first lower and then raise the magazine structure 25. With each lowering of the magazine structure, and as it engages the normally horizontal plate 14, a florist's wire 22 is deposited on said plate and engaged in the clamps 18 in the following manner:

The magazine structure 25 includes double walls 33 and 34 disposed in divergent relation 75 and in the same relative positions as the legs

20 and 21 of the wires 22; a vertical bank of said wires being carried in the magazine structure with the legs of said wires vertically downwardly slidably disposed in corresponding ones of the double walls 33 and 34. The half loops 23 of the wires project forwardly through the slot 16. The double walls 33 and 34 are disposed so that when the magazine structure 25 is in its lowered position in engagement with the plate 14, said walls are disposed directly inwardly of the wire receiving face of the clamps 18. At their lower edge the double walls 33 terminate short of the bottom plate 35 of the magazine structure, whereby to form a horizontal slot 36 through which the legs of wires 22 may be projected outwardly into secured relation in the clamps 18 when the magazine structure is in its lowered position. The clamps 18 are elevated slightly above the plate 14 by spacer plates, as shown, whereby the throat of said clamps 18 falls into register with the slots 36 when the magazine structure is in its lowered position.

Such outward projection of the legs of the florist's wire into the clamps 18 is automatically accomplished, when the magazine structure reaches its lowermost position in engagement with the plate 14, in the following manner:

Within the housing 26 and on the bottom plate 35 there are a pair of slide plungers 37 positioned to project through the slots 36 and to force the adjacent legs of the lowermost florist's wire in the magazine structure outwardly into the clamps 18; said slide plungers being carried in guides 38. The slide plungers 37 are simultaneously actuated, in an outward direction, and from a normally retracted position, by means of a solenoid actuated arrangement which comprises a solenoid 39 mounted vertically in the housing 26 and including a downwardly projecting solenoid plunger 40. The solenoid plunger 40 works against a vertically swingable lever 41 which in turn rides on a horizontal cross head 42. The cross head 42 is fixed on top of and spans between a pair of vertical cam plungers 43 carried in guides 44, and normally held in up position by springs 45. At their lower ends the cam plungers 43 are formed with laterally outwardly facing bevel cams 46 adapted to bear against rollers 47 on the rear ends of the slide plungers 37. Thus, when the solenoid 39 is actuated the solenoid plunger 40 projects forcefully downward, resulting in depression of the cam plungers 43 and outward movement of the rollers 47, causing the slide plungers 37 to project through the slots 36, carrying the adjacent legs of the florist's wire into the clamps 18. Leaf springs 48 engage the rollers 47 on the side opposite the bevel cams 46 and normally maintain the slide plungers 37 retracted.

The cycle of operation of the wire twisting machine is as follows:

With the magazine structure elevated and a florist's wire engaged in the normally horizontal twisting plate 14, the motor 4 is energized in a direction to operate said twisting plate through two full turns; the wire 22 as twisted about a stem 24 then being immediately withdrawn through the vertical slot 16. The electric motor 4 is then reversed to cause rotation of the shaft 7 in an opposite direction and through one full revolution, whereupon the crank 29 causes a lowering, followed by a raising, movement of the magazine structure. As the magazine structure reaches its bottom-most position the solenoid 39 is automatically actuated to discharge one flor-

ist's wire from the magazine structure into the clamps 18 of the twisting plate 14.

The electric circuit, by means of which the above cycle of operations is automatically accomplished, comprises the following:

A push-type switch 49 is mounted on the front panel 2 and includes a switch control plunger 50 projecting both forwardly and rearwardly of said panel; the switch being closed when the plunger 50 is pushed inwardly from in front of the panel, and open when pushed forwardly from the rear. Said switch 49 is interposed in a motor energizing circuit including wires 51 which lead from a supply circuit 52. One of the wires 51 leads direct to one terminal of the reversible electric motor 4, while the other wire 51 leads to the common terminal of a toggle-type reversing switch 53 which is mounted on the frame 8 adjacent but to one side of the shaft 7. From the reversing terminals of the switch 53 a pair of separate motor energizing leads 54 extend to opposite terminals of the motor. When the switch 53 is in the position shown in Figs. 11 and 13, the motor is energized in a direction to operate the twisting plate 14, while said switch 53, when in the position shown in Fig. 12, reverses the motor to cause an operation of the magazine structure.

The switch 53 is automatically reversed, upon completion of each full revolution of the shaft 7, by means of a radially projecting finger 55 adapted to engage the toggle of switch 53 from one side or the other, depending on the direction of rotation; said finger coming to rest against a stop 56 on either side thereof after effecting a corresponding reversal of the switch 53. In order to assure of one full revolution of the shaft 7 before the finger 55 reverses the switch 53, said finger has a certain amount of loose play in a direction circumferentially of said shaft.

It will thus be seen that with the switch 53 in its starting position, as shown in Figs. 11 and 13, the operator, after placing a stem in position to twist a wire thereon, in the manner previously described, pushes inwardly on the plunger 50 of the switch 49. This energizes the motor in the direction which causes rotation of the twisting plate 14, which plate then makes two full revolutions and comes to a stop, in its normal horizontal position, as the finger 55 reverses the switch 53.

With reversal of the switch 53, the electric motor makes one full revolution in an opposite direction, resulting in lowering and then raising of the magazine structure; the entire circuit being broken and reestablished in its initial position when the magazine structure reaches top position. This is accomplished by a trigger 57 mounted on the magazine structure; said trigger being arranged to spring past the plunger 50, without affecting the position of the latter, upon downward movement of the magazine structure, but operative, upon raising of the latter, to push said plunger outwardly whereby to open the switch 49. It is evident that when the switch 49 is opened the entire mechanism ceases to operate, and at which time all of the parts, including the switch 53, have been returned to their initial or starting position.

The solenoid 39 is automatically energized, when the magazine structure reaches its bottom point, by means of matching pairs of contacts 58 and 59 on the magazine structure and frame 8; the contacts 58 being wired to a solenoid cir-

cuit 60, while the contacts 59 are wired to the circuit comprising wires 51. Thus, the instant that the magazine structure reaches its bottom position, the solenoid functions to cause ejection of a wire 22 into the clamps 18, and an instant later—as the magazine carriage begins to rise—the solenoid circuit is automatically broken, whereupon the operating parts of the magazine structure return to normal.

With the above described florist's wire twisting machines, wires can be applied effectively, readily, and automatically to the stems of flowers; and a practical means is supplied for affixing the wires to flower stems other than manually.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as set forth herein.

Having thus described the invention, the following is claimed as new and useful and upon which Letters Patent is desired:

1. A twisting machine for a florist's wire having a pair of divergent legs one of which is adapted to be held against rotation and to have a flower stem disposed therealong, said machine comprising a support, a rotary holder, means rotatably mounting the holder on the support, means on the holder to releasably secure a florist's wire thereon in position with one leg adjacent and extending lengthwise of the axis of rotation of said holder, and means to rotate the holder whereby to wrap the other leg of the wire about said one leg and a flower stem extending therealong; there being releasable catch means operative to engage and maintain said holder in a certain starting position, and the holder rotating means being operative to actuate said plate through a predetermined number of full revolutions from said starting position.

2. A twisting machine for a florist's wire having a pair of divergent legs one of which is adapted to be held against rotation and to have a flower stem disposed therealong, said machine comprising a support, a rotary holder, means rotatably mounting the holder on the support, means on the holder to releasably secure a florist's wire thereon in position with one leg adjacent and extending lengthwise of the axis of rotation of said holder, and means to rotate the holder whereby to wrap the other leg of the wire about said one leg and a flower stem extending therealong; said wire securing means comprising a pair of spaced clamps on the holder in position to engage the divergent legs of the wire, each clamp including a pair of engaged spring pressed elements between which the corresponding leg is adapted to pass for frictional engagement in the clamp.

3. A twisting machine for a florist's wire having a pair of divergent legs one of which is adapted to be held against rotation and to have a flower stem disposed therealong, said machine comprising a support, a rotary holder, means rotatably mounting the holder on the support, means on the holder to releasably secure a florist's wire thereon in position with one leg adjacent and extending lengthwise of the axis of rotation of said holder, and means to rotate the holder whereby to wrap the other leg of the

wire about said one leg and a flower stem extending therealong; the machine including a front panel behind which the holder is rotatable about a substantially horizontal axis at a right angle to said panel, the panel having an access opening adjacent said axis and the wire including a projecting intermediate portion extending through said opening when the wire is secured to the holder, the flower stem extending from said projecting intermediate portion inwardly along said one leg whereby the operator can manually grasp the stem and said portion to prevent rotation of said one leg upon rotation of the holder.

4. A twisting machine for a florist's wire having a pair of divergent legs one of which is adapted to be held against rotation and to have a flower stem disposed therealong, said machine comprising a normally stationary but rotary holder including means to releasably support a florist's wire thereon with one leg of the wire adjacent and lengthwise of the axis of rotation of the holder, means to intermittently rotate the holder in a direction to wrap the other leg of the wire around said one leg and a flower stem extending therealong, a magazine structure carrying a plurality of florist's wires, means mounting said magazine structure for movement between positions clear of and cooperating with said holder, means to transfer a wire from the magazine structure to the holder when said magazine structure is in cooperating position relative to said holder, and means to move the magazine from its clear position to cooperating position and return between said intermittent rotations of the holder.

5. A machine as in claim 4 in which said wire transferring means includes a solenoid on the magazine structure, and means to automatically energize the solenoid when the magazine structure is in said cooperating position relative to the wire holder.

6. A twisting machine for a florist's wire having a pair of divergent legs one of which is adapted to be held against rotation and to have a flower stem disposed therealong, said machine comprising a normally stationary but rotary holder including means to releasably support a florist's wire thereon with one leg of the wire adjacent and lengthwise of the axis of rotation of the holder, the holder being rotatable to wrap the other leg of the wire about said one leg and a flower stem extending therealong, a magazine structure carrying a plurality of said florist's wires, means mounting the magazine structure for movement between a normal position clear of the holder to a cooperating, wire feed position relative thereto, means to automatically feed a wire onto the holder from the magazine structure when the latter is in said cooperating position, power means operative to automatically and alternately rotate the holder in a wire wrapping direction, and move the magazine structure to and from said cooperating position.

7. A twisting machine for a florist's wire having a pair of divergent legs one of which is adapted to be held against rotation and to have a flower stem disposed therealong, said machine comprising a normally stationary but rotary holder including means to releasably support a florist's wire thereon with one leg of the wire adjacent and lengthwise of the axis of rotation of the holder, the holder being rotatable to wrap the other leg of the wire about said one leg and a flower stem extending therealong, a magazine

structure carrying a plurality of said florist's wires, means mounting the magazine structure for movement between a normal position clear of the holder to a cooperating, wire feed position relative thereto, means to automatically feed a wire onto the holder from the magazine structure when the latter is in said cooperating position, and power means operative to automatically and alternately rotate the holder in a wire wrapping direction, and move the magazine structure to and from said cooperating position; said last named means including a reversibly driven shaft, driving connections between the shaft and holder including a clutch arranged to overrun in one direction, and driving connections between the shaft and magazine structure including a clutch arranged to overrun in an opposite direction.

8. A twisting machine for a florist's wire having a pair of divergent legs one of which is adapted to be held against rotation and to have a flower stem disposed therealong, said machine comprising a normally stationary but rotary holder including means to releasably support a florist's wire thereon with one leg of the wire adjacent and lengthwise of the axis of rotation of the holder, the holder being rotatable to wrap the other leg of the wire about said one leg and a flower stem extending therealong, a magazine structure carrying a plurality of said florist's wires, means mounting the magazine structure for movement between a normal position clear of the holder to a cooperating, wire feed position relative thereto, means to automatically feed a wire onto the holder from the magazine structure when the latter is in said cooperating position, and power means operative to automatically and alternately rotate the holder in a wire wrapping direction, and move the magazine structure to and from said cooperating position; said last named means including a reversible electric motor, driving connections between the motor and said holder and magazine structure arranged to actuate the former when the motor runs in one direction and to actuate the latter when the motor runs in the opposite directions, and instrumentalities operative to automatically reverse the motor after a predetermined number of revolutions in each direction.

9. A machine as in claim 8 in which the motor is included in a reversing circuit; said instrumentalities including a reversing switch in the circuit, a motor driven shaft adjacent the switch, the latter including a lever movable in opposite directions to reverse the motor, and a member radiating from the shaft in position to engage and throw said lever on opposite sides dependent on the direction of rotation of the shaft.

10. A machine as in claim 8 in which the motor is included in a reversing circuit; said instrumentalities including a reversing switch in the circuit, a motor driven shaft adjacent the switch, the latter including a lever movable in opposite directions to reverse the motor, and a member radiating from the shaft in position to engage and throw said lever on opposite sides dependent on the direction of rotation of the shaft; said member having limited loose play circumferentially of the shaft so that the latter may make one full revolution between reversing throws of said lever.

11. A twisting machine for a florist's wire having a pair of divergent legs one of which is adapted to be held against rotation and to have a flower stem disposed therealong, said machine

comprising a normally stationary but rotary holder including means to releasably support a florist's wire thereon with one leg of the wire adjacent and lengthwise of the axis of rotation of the holder, the holder being rotatable to wrap the other leg of the wire about said one leg and a flower stem extending therealong, a magazine structure carrying a plurality of said florist's wires, means mounting the magazine structure for movement between a normal position clear of the holder to a cooperating, wire feed position relative thereto, means to automatically feed a wire onto the holder from the magazine structure when the latter is in said cooperating position, power means operative to automatically and alternately rotate the holder in a wire wrapping direction, and move the magazine structure to and from said cooperating position, said power means including a reversible electric motor, a circuit for the motor, a reversing switch in the circuit, means arranged to reverse said switch after a predetermined number of motor revolutions in each direction, an "on-off" switch in the circuit adapted to be manually placed in "on" position, and means actuated by a movable part of the machine to place said latter switch in "off" position upon completion of each cycle comprising one wire wrapping operation of the holder followed by a wire feed operation of said magazine structure.

12. A twisting machine for a florist's wire having a pair of divergent legs one of which is adapted to be held against rotation and to have a flower stem disposed therealong, said machine comprising a base, a support upstanding from the base, a shaft journaled on and projecting horizontally from the support, a normally horizontal and stationary holder mounted in connection with the shaft for rotation therewith, said holder including means on top thereof to releasably secure a florist's wire with one leg thereof adjacent and lengthwise of the axis of rotation, the holder being rotatable to wrap the other leg of the wire about said one leg and a flower stem extending therealong, a florist's wire feeding magazine structure, means mounting the latter in connection with the support for vertical reciprocal movement between a normally raised position and a lowered position relative to the holder, the magazine structure when lowered being operative to feed a wire to the holder, means arranged to automatically actuate the magazine structure when the same move to said lowered position, and power means arranged to automatically and alternately rotate said shaft and holder in a wire wrapping direction and to reciprocate said holder.

13. A twisting machine for a florist's wire having a pair of divergent legs one of which is adapted to be held against rotation and to have a flower stem disposed therealong, said machine comprising a base, a support upstanding from the base, a shaft journaled on and projecting horizontally from the support, a normally horizontal and stationary holder mounted in connection with the shaft for rotation therewith, said holder including means on top thereof to releasably secure a florist's wire with one leg thereof adjacent and lengthwise of the axis of rotation, the holder being rotatable to wrap the other leg of the wire about said one leg and a flower stem extending therealong, a florist's wire feeding magazine structure, means mounting the latter in connection with the support for vertical reciprocal movement between a normally raised position

and a lowered position relative to the holder, the magazine structure when lowered being operative to feed a wire to the holder, means arranged to automatically actuate the magazine structure when the same moves to said lowered position, and power means arranged to automatically and alternately rotate said shaft and holder in a wire wrapping direction and to reciprocate said holder; said power means including a reversible electric motor, another shaft journaled on the support, the motor reversibly driving said other shaft, a crank connected between said other shaft and the magazine structure in operating relation to the latter, a driving connection between said shafts, and clutches interposed between the holder and crank and the corresponding shafts, said clutches overrunning in opposite directions.

14. A wire feeding magazine structure for florist's wires having divergent legs, said magazine structure including an upstanding housing having vertical double walls spaced apart and corresponding in angular position to the divergent legs of the wires, a bank of the latter having their legs vertically movably engaged in said walls, the housing including a bottom and the walls terminating short thereof to provide slots through which the legs of the lowermost wire of the bank may be projected outwardly, and means in the housing operative to engage said legs of the lowermost wire and projecting the same through the slots.

15. A wire feeding magazine structure for florist's wires having divergent legs, said magazine structure including an upstanding housing having vertical double walls spaced apart and corresponding in angular position to the divergent legs of the wires, a bank of the latter having their legs vertically movably engaged in said walls, the housing including a bottom and the walls terminating short thereof to provide slots through which the legs of the lowermost wire of the bank may be projected outwardly, and means in the housing operative to engage said legs of the lowermost wire and projecting the same through the slots; said last named means including normally retracted slide plungers in the housing positioned for passing through the slots, a solenoid mounted in connection with the housing, and operating connections between the solenoid and slide plungers.

16. A wire twisting machine for twisting a florist's wire and which wire consists of a relatively straight leg, a second leg extending laterally out at an angle to the straight leg and a loop connecting adjacent ends of the legs, such machine comprising a support, an element mounted in the support for rotation about an

axis, means to rotate the element, a pair of gripping members on the element and rotatable therewith, one such member being in substantially axial alignment with the axis of rotation of the element and in which the straight leg of the wire may be disposed in substantial alignment with such axis of rotation, the other member being spaced laterally out from the first member and in which other member the laterally extending leg of the wire may be disposed.

17. A machine as in claim 16 including means for automatically feeding wires to the gripping members in timed relation to a predetermined number of rotations of the rotating element.

18. A machine as in claim 16 in which the rotatable element is a relatively flat plate, the two gripping members upstanding from the face of the plate.

19. A device as in claim 18 in which the plate is cut away for a predetermined distance at the corner of the plate adjacent which the juncture of the legs of the wire will lie when such legs are held in the gripping members.

20. A wire twisting machine for twisting a florist's wire and which wire consists of a relatively straight leg, a second leg extending laterally out at an angle to the straight leg and a loop connecting adjacent ends of the legs, such machine comprising a support, a shaft rotatable in the support, an attachment head fixed to one end of the shaft, a plate fixed to the head, the face of the plate lying in a plane outside the axis of rotation of the shaft, a pair of gripping members upstanding from the face of the plate and rotatable therewith, one gripping member being in line with the axis of rotation of the shaft and operable to receive the straight leg of one of such wires, the other gripping member being spaced laterally out from the first member and operable to receive the laterally extending leg of such wire.
